UNITED STATES PATENT OFFICE.

WILLIAM L. CASADAY, OF SOUTH BEND, INDIANA.

TUBE-CLEANER.

No. 836,629.

Specification of Letters Patent.

Patented Nov. 20, 1906.

Application filed January 26, 1903. Serial No. 140,679.

To all whom it may concern:

Be it known that I, WILLIAM L. CASADAY, a citizen of the United States, and a resident of the city of South Bend, county of St. Joseph, and State of Indiana, have invented certain new and useful Improvements in Tube-Cleaners; and I do hereby declare that the following is a full, clear, and exact description of the same, reference being had to the accompanying drawings, and to the letters of reference marked thereon, which form a part of this specification.

This invention relates to improvements in boiler-tube cleaners of that class in which a rotative cutter or scraper is inserted in the tube for the purpose of removing the accumulations of scale which accumulates in water-tube boilers sufficiently to close the tubes entirely sometimes. Heretofore many different constructions have been devised for this purpose, some of which have been provided with rotatable scrapers. Usually, however, after a short period of use the scrapers or cutters become worn and less effective. Many times the tubes are coated on the interior with an indurated shell of lining material which resists the ordinary cleaner and which in some instances is not removable except at great expense in time and labor.

The object of this invention is to provide a construction in the nature of a rotary reamer provided with independently-rotatable cutters or scrapers; which when the device is in operation serve to cut away and remove the scale, leaving the tubes perfectly clean. While the cleaner may be operated by hand, if preferred, the same is more particularly designed as a power-cleaner and may be driven from any desired source of power.

The invention embraces many novel features; and it consists in the matters herein-after described, and more fully pointed out and defined in the appended claims.

In the drawings, Figure 1 is a side elevation of a device embodying my invention. Fig. 2 is a central longitudinal section thereof. Fig. 3 is a section taken on line 3 3 of Fig. 1, showing the same in operation in a flue. Fig. 4 is a section taken on line 4 4 of Fig. 1. Fig. 5 is a side elevation of one of the rotary cutters or scrapers. Fig. 6 is a longitudinal section thereof after the same has become somewhat worn through use. Fig. 7 is an enlarged perspective view of one of the sliding arbors for the cutters. Fig. 8

is an enlarged side elevation illustrating the operation. Fig. 9 is an end elevation of the same.

As shown in said drawings, A indicates a shaft of any desired kind adapted to be rotated manually or from any desired source of power and detachably connected with the head B, in the rear end of which is provided a socket adapted to receive the end of said shaft and through which passes a pin a. Said head is provided in its inner end with a plurality of eccentric recesses, as shown in Fig. 3 three in number, which open through the side of the head B at equal distances apart. At the rear end of each of said recesses or on the end adjacent to the shaft A is provided a narrow slightly-curved slot b, arranged eccentrically with the axis of the head and which at the outer end each opens partly through the side of the head, as shown in Figs. 1 and 3. On the inner or front end of said head is fitted a removable chuck B', the rear end of which is shaped to engage over the ends of the web portions of the head B between the recesses. Said chuck, as shown, comprises the enlarged rear end portion b⁴, which engages over the end of the head, as before described, and which is provided with integral side members b² b², the extremities of which are integrally connected, as shown in Figs. 1 and 2, thereby providing an opening extending transversely through the chuck. In the rear end of said chuck adjacent to the head B is provided grooves or slots b', corresponding with the grooves or slots b, but of less width and less length than said last-named slot and having less eccentricity with respect to the axis of the head than has said slots b'. Seated in the said grooves or slots b b' are the sliding non-rotative shafts C, provided at the rear end with the oblong and slightly-curved heads c, which engage in the slots b and the reduced flattened opposite or front ends which engage in the slots b'. An independently-rotatable cutter or scraper D is rotatably secured upon each of said shafts in position to project beyond the periphery of the head and free to slide with the shafts longitudinally of said slots b b'. From the construction described it is obvious that said cutters will slide outwardly when the head is rotated in one direction and slide inwardly when the head is rotated in the other, since the contact of said cutters with the inner side of the tube or with the coating thereon will retard the cutters and

force them to the ends of the slots opposite from the direction of the rotation of the head. Centrifugal force greatly aids during the cutting operation to force said cutters outwardly 5 of the slots into cutting engagement with the scale on the inner surface of the tube. Said cutters D, as shown, are larger at one end than at the other and are arranged on said shafts C with the smaller end directed forwardly and, as shown, are provided with a sharp edge or V-shaped thread or spiral cutting and scraping rib adapted to rotate against the inner surface of the tube X, as shown in Fig. 3, when the device is in operation, and owing to the difference in the 10 lengths and eccentricity of the slots b and b' with respect to each other the rear ends of the cutters D tend to be thrown farther outward than the front ends thereof, causing 15 said cutters to assume a position oblique to the axis of the head. Two of said cutters D', similar to the cutters D, are provided in the chuck B. As shown, non-rotatative shafts C' C² are seated at their inner ends in the 20 larger or rear end of the chuck and at their forward or outer ends are provided with thin flat heads which engage at the forward end. The end of the chuck is provided with a transverse groove or seat to receive the drill-bit E, 25 which fits closely in said seat and at the extremity is shaped approximately to cut the scale as a drill. If desired, said bit may be given a slight twist to insure clearance. An aperture is provided transversely through said bit, 30 and the seat end is also axially apertured to receive the end of the bolt A², which extends through the head, chuck, and seat end of the bit and the head of which is engaged in the shaft-socket. The threaded end of said bolt 35 extends into the transverse aperture in the bit and is provided with nuts to hold the parts in operative relation.

The operation is as follows: When the cleaner is rotated rapidly in the tube X, as 40 shown in Fig. 3, and in the direction indicated by the arrow Y, the contact of the cutters D with the flue, together with centrifugal force, tends to slide the shafts C outwardly toward the periphery of the head, throwing said cutters or scrapers into operative engagement 45 with the interior of the tube and causing the same to rotate oppositely from the rotation of the head, as indicated by the arrow Z. Obviously said cutters or cleaners are thus 50 pressed into close contact with the interior of the tube, the thread-like shape of the cutting or cleaning surface acting to break up, scrape out, and remove any interior adherent matter, whether ordinary boiler-scale or other 55 undesirable material. The drill-bit E and cutters or scrapers D' being disposed in advance of the cutters or scrapers D and held at unvarying distances with respect to the 60 axis serve to start the operation, removing a portion of the scale from the tube, and prepar-

ing the way for the cutters or scrapers D, the closeness of engagement of which against the interior of the tube will depend upon the rapidity of the rotation of the head and the obliquity of the slots b and b'. It is obvious 70 that inasmuch as the rear slots b are longer than the slot b' and extend nearer the periphery of the head that the rear ends of the cutters are thrown outwardly into closer contact with the flue than the front ends of the 75 same. It follows that the wear on the cutters is greatest and most rapid toward the rear end of the cutters, the cutters eventually through long-continued use assuming the form shown in Fig. 6, in which the V-shaped 80 threads at the rear end of the same are much worn. When this occurs, it is only necessary to turn said cutters end for end, when the device will operate as before, thus enabling the cutters or cleaners to be used much longer 85 than would otherwise be the case and at the same time insuring the most effective operation of the device, inasmuch as the pressure of the cutters against the material to be removed and against the interior of the flue increases progressively from the front end of the device to the rear end of the cutter D. Obviously the number of cutters or cleaners may be varied, and other devices may be used in conjunction therewith, and the heads 90 95 may be rotated manually or power may be used, as preferred. When it is desired to remove the device from the tube, it only is necessary to stop or to reverse the rotation thereof, when the cutters D are forced inwardly to the inner ends of the slots, thereby releasing their engagement with the tube and permitting the device to be freely withdrawn.

Obviously many details of construction 105 may be varied without departing from the principles of this invention.

I claim as my invention—

1. A tube-cleaner comprising a rotative head having a plurality of recesses therein 110 and a slot at each end of each recess and a rotative cutter in each recess adapted to slide longitudinally of said slots when the head is rotated.

2. A tube-cleaner comprising a recessed 115 rotative head having curved slots therein eccentric to the axis of the head and eccentric to each other, a rotative cutter journaled in each recess and adapted to move outwardly in said slots when the head is rotated in one direction and inwardly when rotated in the opposite direction.

3. A tube-cleaner comprising a rotative head having oppositely-disposed slots there-in of different eccentricities with respect to 125 the axis of the head and a cutter slidably engaged in said slots and adapted to move inwardly or outwardly of said head dependent upon the direction of rotation.

4. In a device of the class described the 130

combination with a rotative, recessed head of a plurality of cutters thereon having fixed axes of rotation, and a plurality of cutters extending longitudinally of the head and slidably engaged at each end therein in slots having different inclinations.

5. The combination with a rotative recessed head, having slots in the ends of said recess eccentric to each other and part of 10 which open through the periphery of said head and a plurality of rotative cutters carried in said slots and adapted to be thrown inwardly or outwardly of said recesses dependent upon the direction of rotation of said head.

15 6. The combination with a rotative head, having a plurality of recesses in the periphery thereof and eccentric slots at the ends of said recesses, those at one end being longer than those at the other and at an inclination thereto, a shaft slidably engaged in said slots and rotative cutters thereon adapted to be thrown outwardly when the head is rotated in one direction and to fall inwardly when rotated in the other.

20 7. In a tube-cleaner the combination with a rotative head having a plurality of outwardly-opening recesses therein, of a removable chuck thereon, a blade on the forward end of said chuck, means connecting said blade, chuck and head axially, a plurality of rotative cutters in said chuck and a plurality of rotative cutters slidably engaged in grooves at the ends of said recesses, the grooves in each recess being arranged out of alinement 25 with each other.

30 8. A tube-cleaner comprising a head hav-

ing a plurality of recesses therein each having slots at the ends thereof eccentric to each other, a removable chuck on said head, means connecting said head and said chuck 40 axially, a plurality of slidable shafts in said slots, a head on each complementary with said slots and a rotative cutter on each shaft.

9. A tube-cleaner comprising a head having a plurality of recesses therein and slots in 45 the ends of said recesses eccentric with each other, a shaft slidably engaged in the slots of each recess and a rotative cutter journaled thereon.

10. A rotatable head for the purpose specified provided with three equally-spaced recesses in the sides thereof, an eccentric slot at the rear end of each recess, a chuck adapted to be rigidly secured on the front end of the head and forming the other end of the recess and provided with slots therein eccentric to the aforesaid slots, shafts slidably secured in said slots in each recess, a rotatable conical cutter journaled on each of said shafts, a V-shaped spiral rib or thread extending around the same, other cutters in advance of the last-named cutters so disposed that the action of the cutters in the tube progressively increases from the front to the rear of the head. 55

In testimony whereof I have hereunto subscribed my name in the presence of two subscribing witnesses.
